UNITED STATES PATENT OFFICE.

PAUL KRAUTZ, OF BERLIN, GERMANY, ASSIGNOR TO C. KRAMME, OF SAME PLACE.

SUSPENDING DEVICE FOR ELECTRIC LAMPS.

SPECIFICATION forming part of Letters Patent No. 340,512, dated April 20, 1886.

Application filed December 14, 1885. Serial No. 185,619. (No model.)

To all whom it may concern:

Be it known that I, PAUL KRAUTZ, engineer, a subject of the King of Prussia, residing at Berlin, Prussia, German Empire, have invented certain new and useful Improvements 5 in Suspending Devices for Electric Lamps and Chandeliers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to incandescent electric lights, and the purpose thereof is to provide the same with an improved construction which will allow of the lamps being raised and lowered without the necessity of employing free hanging wires, thereby avoiding the annoyance heretofore occasioned by such wires being brought in contact with each other or with parts of the chandelier-fitting.

20 My invention is applicable to a stand containing two or more lights, and may be used in combination with fixed lamps as well as with separately-movable lamps.

25 My invention consists in the several novel features of construction and combinations of parts hereinafter fully described, and definitely pointed out in the claims annexed to this specification.

30 Referring to the drawings forming part of this application, Figure 1 is a view partly in elevation and partly in section, illustrating my invention. Fig. 2 is a partial longitudinal section of Fig. 1, enlarged. Fig. 3 is a cross-section of the same, enlarged.

35 In the drawings the reference-letter *a* designates an outer tube, provided with an external thread, *a'*, at the top, which engages with a female thread in a socket-piece, *b'*, mounted on a short tube, *b*, having a diminished threaded end, which receives a nut, *b''*, by means of 40 which a hook, *c*, may be attached in the manner shown.

45 Upon the lower end of the tubes *a* is formed a screw-thread, *a''*, which engages with a thread

upon a cap, *d*, closed at its lower end. The stationary or fixed lamps are attached to the closed end of this cap, as shown in Fig. 1.

Within the tube *a*, and extending the entire length thereof, are placed two strips, *f*, made of any suitable non-conducting material. These strips serve to hold and insulate rods *e* coextensive with the length of the strips, and made of copper or other suitable conducting material. These rods are each soldered at the upper end to one of the electric service-wires *e'*, which pass through the tube *a*, and are connected in the usual manner to the line-wires. The two rods are braced by rings *f'* and *f''* at top and bottom, made of ebonite, rubber, or other non-conducting material.

Upon the rods *e* slide segmental pieces *g*, 65 having grooves which receive and fit the rods. These pieces, which are of any conducting material, are attached to and move with a core-piece, *h*, made of wood or other non-conducting material. This core-piece is mounted 70 upon a tube, *k*, into which pass the wires *i*, soldered to the contact-pieces *g*. These wires pass down the tube and to the lamp *l*, where the usual connection with the contact-key or switch is made. There is sufficient friction 75 between the contact-pieces *g* and the rods *e* to hold the lamp *l* at any point to which it may be adjusted. This construction secures not only the result of giving proper contact between the conductors, but also provides sufficient friction to retain the lamp at any point. 80

Within the cap *d* is placed a ring, *n*, of wood or other non-conducting material, into which ring are set two half-rings, *p*, insulated from one another, and each of which is connected with one of the rods *e* by means of a short wire, *o*. A wire passes from each of the half-rings *p* through the hollow brackets *q*, which are mounted on the closed end of the cap *d*, and thence connect with the lamps *l* 90 mounted on the fixed brackets *q*.

It will be seen that the rods *e* subserve three distinct purposes: First, they conduct the current to the fixed lamps; second, they serve as conductors in the tube *a*, and, finally, they 95 carry the current to the lamp *l*, besides giving

friction to the core-piece and its contacts to enable it to sustain the lamp *l*.

Instead of a single movable lamp, I may use a number electrically connected by separate 5 half-rings in a manner similar to that already described.

Instead of an incandescent, I may use an arc light, and I may also wholly dispense with the stationary or fixed lamps.

10 What I claim is—

1. The combination, with the outer tube of a suspension device for electric lamps, of longitudinal segmental strips of non-conducting material, vertical stationary conducting rods 15 located in said strips, service-wires connected with said rods, a tubular lamp-carrying rod provided at its inner end with grooved contact-pieces engaging and sliding on the conducting rods with frictional contact, to hold 20 the tubular rod in any position to which adjusted, and electrical conductors attached to the contact-pieces and entering into the tubular rod, substantially as described.

2. In a vertically-adjustable electric lamp, 25 the combination, with a tube, insulating-strips

therein, and conducting-rods mounted on said strips, of a core-piece carrying contacts sliding on the conductors, wires soldered to the contacts, a tube attached to the core-piece and containing said wires, and a lamp carried by 30 the tube.

3. In an electric light, the combination, with a tube, insulating-strips contained therein, and conducting-rods mounted on the same, of a core-piece carrying contacts and sliding on 35 the conductors, wires soldered to the contacts, a tube attached to the core-piece and containing said wires, an insulating-ring beneath the conducting-rods, conducting-pieces set in said ring and connected with the rods by wires, 40 and stationary and movable lamps, the latter on the tube and the former on fixed brackets, substantially as described.

In testimony whereof I affix my signature in presence of two witnesses.

PAUL KRAUTZ.
